UNITED STATES PATENT OFFICE.

GREGORY JOHN SPOHRER, OF FRANKLIN, PENNSYLVANIA.

ENGINE-STARTER.

1,056,600.

Specification of Letters Patent. Patented Mar. 18, 1913.

Application filed March 19, 1912. Serial No. 684,719.

To all whom it may concern:

Be it known that I, GREGORY J. SPOHRER, a citizen of the United States, and a resident of Franklin, in the county of Venango and State of Pennsylvania, have invented a new and Improved Engine-Start, of which the following is a full, clear, and exact description.

My invention relates to an engine starter, and an object of my invention is to provide a new and improved form of device in which a fluid-actuating element is positively brought into engagement with the engine mechanism after a back firing action on the part of the latter.

A further object of my invention is to provide in those engine starters where the passage of the actuating fluid is controlled by a valve riding on an actuating member, a valve control which is an integral part of the actuating mechanism.

A further object of my invention is to provide a new and novel form of clutch-actuating mechanism in a device of the above-identified character.

A still further object of my invention is to provide a pneumatically actuated starter, the exhaust from which is through a compactly arranged casing for the movable elements, which casing additionally acts as a muffler.

I attain the above-outlined objects by mounting the casing containing the actuating mechanism on the end of the cylinder through which projects the piston rod, and provide a by-pass leading around the piston head at the end of its stroke, so that the actuating fluid will pass from the back of the piston head and exhaust into the casing before it is allowed to pass into the outside atmosphere, thereby utilizing the casing as a muffler. Further, I position the valve stem controlling the actuating fluid in a groove in the piston stem rather than on the separate track heretofore used, and I bring the clutch members on the engine shaft into engagement by means of a rotating pin-and-slot connection, which will advance the clutch members by frictionally holding one of said members against rotation while permitting a longitudinal movement of the same.

Reference is to be had to the accompanying drawings, forming a part of this speci-

fication, in which similar characters of reference indicate corresponding parts in all the figures, and in which—

Figure 1 is a longitudinal sectional view taken through a preferred embodiment of my invention; Fig. 2 is a transverse sectional view taken on the line 2—2 of Fig. 1; Fig. 3 is a transverse sectional view taken on the line 3—3 of Fig. 2; Fig. 4 is a transverse sectional view through the piston cylinder and taken on the line 4—4 of Fig. 1; Fig. 5 is a transverse sectional view taken on the line 5—5 of Fig. 2, showing a clutch-actuating mechanism, and Fig. 6 is a side elevation of the turning gear and attached parts.

Described more in detail I have shown a cylinder 6, suitably closed at one end by means of a head 7 containing a centrally-disposed screw-threaded inlet 8, the opposite end of which cylinder is suitably closed by a head 9 forming part of a gear casing 10. Slidably mounted in the cylinder 6, is a piston comprising a head 11 of any suitable construction, extending from which and passing through an opening 12 in the head 9 and through an aligned opening 13 in the casing 10, is a piston stem 14. The under side of the piston stem is formed into a rack 15, the two outermost teeth 16 of which rack are slidably mounted in transversely-disposed pockets 17, and each tooth is held in projected position by means of a compression spring 18, one end of which spring is disposed within a recessed pocket 19 in the respective tooth, the other end of which spring bears on a suitable closing cap 20. The rack 15 is permanently in mesh with a spur wheel 21, which spur wheel is suitably journaled within the casing 10 and disposed with its axis transversely of the line of movement of the stem 14.

Extending integral from one side of the spur wheel 21, is a shaft 22 having a square end 23, by means of which the engine may be started, as is common with hand-crank devices of this character now in general use. Extending from the opposite side of the spur wheel 21 and concentrically disposed relative to the wheel and the shaft 22, is a hollow cylinder 24, which cylinder has an elongated aperture 25 therein extending transversely of the axis of the cylinder. Mounted within the cylinder 24, is a slid-

ing block 26 carrying a transversely-disposed pin 27 extending beyond opposite sides of the block and into the alined slots 25 in the opposite sides of said cylinder.

5 It will be seen by the above-outlined construction, that a rotation of the spur wheel 21 or the actuation of the shaft 22 by a hand-wheel, will rotate the cylinder 24 and should the block 26 be held from rotation, 10 such a movement would advance said block. This block 26 is held in frictional engagement with the casing 10 by means of a friction ring 28 (see Fig. 3), which friction ring is held to the casing 10 by means of a 15 screw 29. This friction ring being split at 30 and sprung out of its normal circumference will have a tendency to grip the sliding block 26, and, as shown in Fig. 3, a bearing ring 31 is disposed between the 20 friction ring and the forwardly-projecting portion of the sliding block 26. A sliding key 32 connects this bearing ring with the sliding block 26.

Threaded into the outer end of the sliding block 26 and in axial alinement with the spur wheel 21 and shaft 22, is a stub shaft 33 and a clutch member 34, the coacting portion 35 of which clutch is connected to the engine shaft 36. The teeth on the 30 clutch are so arranged that when the device is turned through the actuation of the engine itself, the two parts of the clutch are disconnected, the incline of the teeth forcing the clutch member 34 and its attached sliding block 26 back into the cylinder 24, but on the actuation of the spur wheel 21 and its attached parts, the sliding block 26 is forced forward bringing the clutch members into engagement. As is common with devices of 35 this character, the actuating fluid is admitted through the inlet 8 to act on the head 11, forcing the piston to the left, as shown in Fig. 1, thereby actuating the spur wheel 21, as hereinbefore described.

40 It is desirable in constructions of this character, to automatically shut off the supply of fluid through the inlet 8, and for this purpose, there is carried by the casing 10, a valve 40 having an inlet 38 from any suitable source of compressed actuating fluid, and an outlet 39, the latter being in fluid connection with the aforesaid inlet 8. The 45 passage of fluid from the inlet 38 to the outlet 39 is controlled by the valve 40, the end of the stem 41 of which is positioned in a groove 42 cut in the upper side of the piston stem 14. This valve is maintained in 50 position with its end engaging the bottom of the groove 42 by means of a compression spring 43 bearing thereon. While this arrangement of a valve controlled by the position of the actuating piston stem is disclosed in my application, Serial No. 635,930 55 filed June 11, 1911, the advantage of this 60 construction lies in the fact that the groove 65

42 can be easily milled in the stem and eliminates the separate track arrangement heretofore disposed on top of the piston stem, thereby forming a piston stem of one piece.

70 In order to form a combined muffler and exhaust, the head 9 and the casing 10 may be made integral and have a projecting band 44 telescoping and in threaded engagement with one end of the cylinder 6. A series of outlet apertures 45 are extended 75 through the cylinder 6 within the band 44 and are so positioned relative to the adjacent end of the cylinder that the actuating fluid which has passed through the inlet 8 to act on the back of the piston head 11, also 80 acts through the by-pass formed by the apertures 45, passageways 46 and apertures 47, through the opening 12 into the casing 10, and through the opening 13 to the outside atmosphere. In this way, it will be seen 85 that when the piston head 11 has reached the position between the apertures 45 and 47, the actuating fluid in the cylinder 6 will 90 pass through the casing 10, which acts as a muffler, before it is passed to the outside atmosphere. At the same time, the valve stem 41 having reached the depressed portion of 95 the groove 42 adjacent the piston head, permits the actuation of the spring 43 to stop the passage of the actuating fluid through the outlet 39 and inlet 8. This balancing of fluid pressure on opposite sides of the piston head 11, will, of course, act as a cushion to the piston, but as a further precaution, a circular buffing ring 48 may be carried by 100 the head 9 projecting into the cylinder 6 and disposed about the opening 12.

105 As is usual with devices of this character, the actuation of the stem 14 winds a spring which returns the piston to its original position to be actuated on the next stroke, and for this purpose there is mounted upon the shaft 22, a gear wheel 49, which gear wheel is permanently in mesh with the teeth of the rack 15 and has attached 110 thereto one end of a coil spring 50, the opposite outer end of which is suitably attached by means of a pin 51, with some portion of the casing 10. By this construction, it will be seen that the actuation of the stem 115 14 places the spring 50 under tension, so that when the rack is free to move back to its original position adjacent the inlet 8, the spring will operate to so move it.

Having thus described my invention, I 120 claim as new and desire to secure by Letters Patent:

1. In an engine starter, a gear wheel having a cylinder projecting from one side thereof, said cylinder having elongated 125 diagonally-disposed apertures in opposite sides, a block slidably mounted in said cylinder, a clutch member carried by said block, said block having a pin extending from opposite sides thereof and disposed in said ap- 130

- ertures, and means frictionally holding said block whereby the rotation of said gear wheel will advance said clutch member.
2. In an engine starter, a cylinder, a block slidably mounted in said cylinder, a clutch member carried by said block, means for advancing said block on the rotation of said cylinder, and a friction band engaging said block to retard the rotation of the same.
3. In an engine starter, a cylinder, a gear casing forming one head thereof, a piston mounted in said cylinder and extending through said casing, and a by-pass permitting the passage of fluid from the rear of said piston to the opposite face when the latter has reached the limit of its actuating stroke, said by-pass leading into said casing, said casing acting as a muffler.
- In testimony whereof I have signed my name to this specification in the presence of two subscribing witnesses.

GREGORY JOHN SPOHRER.
